REINFORCED KEY

Irving Alfred Epstein, Fitchburg, Mass., and Adolphe J. Girard, Lausanne, Switzerland, assignors to Independent Lock Company, Fitchburg, Mass., a corporation of Massachusetts

Filed Apr. 20, 1962, Ser. No. 189,086

4 Claims. (Cl. 40—330)

This invention relates to a key device, and more particularly to an ornamental key of the type used for operating the locks of automobiles, doors or the like.

Still more particularly, this invention relates to a key having decorative indicia bearing insert means fixed to the head or bow thereof characterized by ease of affixation of the insert onto the key head and further characterized by permanence of attachment of the insert to the head.

In the past, it has been proposed to provide a key to which there may be affixed plates bearing indicia, such as monograms, initials, or other identifying or decorative matter. The plates have been secured to the key head or bow by a variety of means, including threaded fasteners, mechanical spring retainers, soldering, brazing and the like. It has also been proposed to affix the plate to the key through the use of an adhesive bond, the present invention being directed to an improved construction of the latter sort.

In forms of the mechanically and the adhesively bonded constructions heretofore known, the key has been provided with a recess or depression, the indicia bearing plate having border dimensions corresponding substantially with those of the depression, being, respectively, fastened or bonded within the depression. While reasonable permanence of attachment between the key and the plate has been obtained through the use of mechanical fastener means, such means greatly increase the cost of production of the device and the time required for assembling the plate with the key.

Also, since such fastening device is normally visible on the surface of the key, the attractive appearance thereof is marred.

It will be observed from the above that adhesive bonding of the plate to the key is thus preferable both from the economic and the appearance standpoints. However, despite the advantages of adhesive bonding, and the development of myriad highly effective adhesive substances and formulations, no key device heretofore available has enabled the formation of a reasonably permanent adhesive bond between the plate or insert and the key.

The unsatisfactory nature of such devices is believed to be due, in a measure, to the failure of the art to appreciate that the affixation by adhesive of a plate or insert to a key involves special problems. These problems are occasioned by the fact that the key head or bow is a torque transmitting agency, and that in the normal use of a key there will be a flexure or deformation of a more or less temporary duration of the bow or head portion thereof. It is common knowledge that a key is used by inserting the shank or tumbler orienting portion into the rotatable plug of a lock mechanism, and thereafter twisting the head or bow portion thereof.

In certain instances, particularly where rotation of the plug is employed to withdraw a spring projected latch bolt or the like, considerable torque must be applied by the fingers of the operator to the key head. In other instances, where the plug may, in normal use, require little torque for its operation, a large torque may occasionally be required or applied by the operator due, for example, to a temporary jamming of the plug, an improper insertion of the key shank into the plug, or an

2

attempt to turn the plug beyond its intended limiting rotated position.

The application of torque in the manner aforesaid results in a twisting of the key head and, in adhesively bonded ornamental keys before known, has resulted in a more or less gradual deterioration or abrogation of the bond between the plate and the key by inducing strains in the key head which, in turn, cause a relative movement between the plate and the key. It will be recognized that such relative movement will compromise the bond of even a relatively flexible rubber adhesive in that air, moisture or detritus may be admitted between the bonded parts. Although the relative movement aforesaid may be very slight, the net effect will be the eventual loosening and displacement of the plate from the key, such eventuality being accelerated where the key is frequently employed.

It should be noted that the employment of a depressed area or recess for receiving the adhesively bonded plate in keys heretofore known magnifies the problem since such area provides a thin section directly behind the plate, and thus permits a high degree of relative flexing movement between the key and plate at such relatively weakened area.

Accordingly, the present invention has for an object the provision of an improved, adhesively bonded key and plate device, eliminating the tendency experienced in bonded devices heretofore known for the plate to become dislodged after use.

A further object of the invention is to provide a key device of the type described including a depressed or recessed area within which the plate or insert may be positioned, which device is constructed in a manner to prevent relative movement of the plate and key upon the application of torque to the key head.

Still a further object of the invention is the provision of a device of the class described wherein the face opposite the plate carrying face presents a novel and decorative appearance.

Still a further object of the invention is the provision of an attractive key device which may be readily "customized" or "personalized" by the adhesive application thereto of a plate or insert carrying indicia or decorative matter.

To attain these objects and such further objects as may appear herein or be hereinafter pointed out, reference is made to the accompanying drawings, forming a part hereof, in which:

FIGURE 1 is an exploded perspective view of a key device in accordance with the invention;

FIGURE 2 is a fragmentary plan view of the head of the key device;

FIGURE 3 is a magnified section on the line 3—3 of FIGURE 2;

FIGURE 4 is a section similar to FIGURE 3 of a prior art key;

FIGURE 5 is a plan view of a key in operating position within a lock assembly (shown in phantom), with a torque applied to the key head.

As shown in FIGURE 1, there is provided a key 10 including a bow or head 11 and a shank or lock operating portion 12. The head or bow 11, in accordance with the invention, is formed on its front face 13 with a concave or recessed portion 14 which, in the illustrated embodiment, is generally rectangular in plan but which need not be restricted to such shape. The portion 14 is outlined or delineated by walls 15, 16, 17, 18. The rear face 20 of the key, in an area registering with the recessed portion 14, is provided with a raised reinforcement portion 21 which, as shown in FIGURE 2, might take the form of an emblem, crest or other decoration. The reinforcement portion 21 optionally but preferably

covers substantially the entire area of the rear face 20 which corresponds to the area of the front face covered by the depressed portion 14.

A plate or insert 30, which may be flat or may, for appearance sake, be cupped or concavo-convex, is secured within recess 14 by an adhesive mass or layer 31 disposed between the rear face 32 of the insert and the floor 19 of the recess 14.

It will be understood that the adhesive or cement employed may be of any type suitable for joining the key 10 and insert 30, both parts normally comprising metal although the use of plastic inserts is contemplated as well. Also, the plate or insert 30 may, for convenience, be pre-coated over its entire back portion with a "stay-wet" type adhesive, such as a water insoluble rubber adhesive, the insert in such case being provided with the usual protective layer temporarily secured to the adhesive, to be removed just prior to use.

Preferably the outline of the insert closely conforms to the inner edges of walls 15, 16, 17, 18, whereby the positioned insert will be engaged with such walls and will aid the cement layer in preventing a shifting of the insert. Also, the overall depth of the insert 30 is such that together with the thickness of the adhesive layer 31, the outer edge of the insert does not project beyond the face 13 of the key.

In FIGURE 3 there is shown in solid lines a sectional view of a key in accordance with the invention. In FIGURE 4 a similar view is shown of a prior art key. The dot and dash lines in each of FIGURES 3 and 4 represent, on a somewhat exaggerated scale, the configurations of the keys upon application of torque to the key bow, with some resistance to turning of plug P of lock cylinder assembly C being assumed. It should be understood that the torsional stresses and strains herein referred to are limited to the head of the key since the shank of the key is received within and maintained in aligned condition by the keyway slot of the plug P.

In both instances there is considerable lateral deflection of the lobes or edges E-E of the bow from the initial planar alignment of the latter. However, it will be seen that the floor 19 of the key in accordance with the invention, FIGURE 3, has been distorted hardly at all from its initial position and that there is thus present no significant flexion or unseating tendency to separate or crack the cementitious mass holding the insert 30 in the recess 14. This is because the reinforcing element 21 has restricted flexion of the bow to the areas of the bow outside of the area wherein the insert is secured.

In contrast, it will be seen in FIGURE 4 that the flexion in the bow of the prior art key is distributed substantially across the entire bow of the key and that there is considerable strain concentrated at the area where the thinner bow section which is recessed for receipt of the insert or plate joins the thicker bow portion or section. It will thus be readily recognized that in the prior art key there will be an eventual separation of the plate from the key bow due to the constant stressing arising from continued operations of the lock plug.

It will thus be seen that while the prior art devices provided a recessed area to aid in assuring a firm attachment between the key and inserts, this area actually weakened or compromised the said attachment.

The reinforced area of the key of the invention effectively contains the distortion of the bow or, more accurately, limits the same to areas outside the critical or attached area and thus is conducive to a secure and permanent connection between the plate and the key bow. While the invention has been illustrated in conjunction with a single plate conforming to the recess area, it is feasible and, in certain applications desirable, (i.e. for initialing), to utilize plural inserts which together conform to the recessed area.

Also the present invention, due to the lack of flexion

in the critical area, permits the use of a wider range of cements than heretofore since a relatively brittle cement may now be employed without fear of cracking or crumbling of the latter.

The above described key device provides a durable, inexpensive and attractive "customized" article. By reason of the constructional features aforesaid, a durable and permanent cemented connection between the key and the plate or insert is obtained, a feature not found in comparable key devices heretofore known.

The reinforcing portion, in addition to performing the functions aforesaid, enhances the appearance of the key. If desired, the floor 19 of the recess may be stamped with a marking 19a which corresponds with or identifies the keyway section of the key to facilitate selection of the proper key by the key cutter and at the same time provides a roughened surface to augment the effectiveness of the adhesive bond.

It will be understood that the described decorative key device is supplied to the locksmith or other key cutter along with plates marked with numerals or other indicia. The locksmith then cuts or bits the key shank in known manner to correspond with the biting or pattern of the key supplied by the customer. The insert or inserts bearing the selected initial or indicia are then mounted in the recess of the key either by application of cement to the rear face of the plate or in the recess or, in the case of an adhesive bearing insert, by stripping the protective layer from the back of the insert and pressing the insert into the recess.

By the construction which has been provided, there may be employed an alloying material of the kind which does not sacrifice rigidity and long wear and which is susceptible of accurate formation by forging, without limitation, an additional feature which may prolong the utility of the union between the emblem 30 and the key bow, during its course of use, even to the point of rigidity of union of the insert or emblem 30 within the seat or recess 14 by a friction fit about its periphery to augment or even substitute for the adhesive union.

Having thus described the invention and illustrated its use, what is claimed as new and is desired to be secured by Letters Patent is:

1. An ornamental key comprising a shank portion and a bow portion, said bow portion being formed to define a recessed area on one face thereof, the other face of said bow portion including a raised reinforcing portion substantially in registry with the recess of said one face and extending outwardly beyond said other face to provide on said bow portion an area having substantial resistance to deformation under torsional stress, independent insert means positioned within said recess and having outer marginal edge portions conforming substantially to the outline of said recess and an adhesive layer interposed between said recess and said insert means and bonding said means to said key, all portions of said insert means lying within said recess and beneath the plane of said one face, whereby said recessed area will be substantially unaffected by torsional stresses applied to said bow to minimize relative movement of said insert with respect to said recess.

2. An ornamental key comprising a shank portion and a bow portion, said bow portion defining a concave area on one face thereof, the other face of said bow portion including raised reinforcing portions in registry with said concave area and spanning an area on said other face substantially coextensive with said concave area, to provide on said bow portion an area having substantial resistance to deformation under torsional stress, independent insert means positioned within said concave area and having outer marginal edge portions conforming substantially to the outline of said last named area, and an adhesive layer interposed between said insert and portions of said concave area and bonding said insert within said area, all portions of said insert means lying within said concave

area and beneath the plane of said one face, whereby said concave area will be substantially unaffected by torsional stresses applied to said bow to minimize relative movement of said insert with respect to said key.

3. A key in accordance with claim 2 wherein said raised reinforcing area includes a coined decorative emblem on the outer face thereof.

4. An ornamental key blank comprising a shank and a bow portion, said bow portion being formed to define a recessed area on one face, the other face of said bow including a raised reinforcing portion substantially in registry with the recess of said one face, and extending outwardly beyond said face to provide on said bow an area having substantial resistance to deformation under torsional stress, whereby independently attachable insert 10

5

means positioned within said recess and having outer marginal edge portions conforming substantially to the outline of said recess, upon being bonded within said recess to said key, will be substantially unaffected by torsional stresses applied to said bow, to minimize relative movement of said insert with respect to said recess.
